[57] CLAIM

The ornamental design for a beverage cup lid, as shown and described.

DESCRIPTION

FIG. 1 is a perspective view of a beverage cup lid showing our new design;

FIG. 2 is a top plan view thereof;

FIG. 3 is a bottom view thereof;

FIG. 4 is a side elevational view thereof;

FIG. 5 is a side elevational view taken 180° from the view of FIG. 4;

FIG. 6 is another side elevational view taken at 90° from the view of FIG. 5;

FIG. 7 is a side elevational view taken 180° from the view opposite of FIG. 6; and,

FIG. 8 is a perspective similar to FIG. 1 with the lid seal in a raised position.

The broken line showing of a cup is for illustrative purposes only and forms no part of the claimed design.
